CLAIM

The ornamental design for a urinary catheter adapter having a filtered air vent, or the like, substantially as shown and described.

DESCRIPTION

FIG. 1 is a perspective view from the front of my new design for a urinary catheter adapter;
FIG. 2 is a top plan view thereof;
FIG. 3 is a front elevational view thereof;
FIG. 4 is a left side elevational view thereof; and
FIG. 5 is a bottom plan view thereof.
